UNITED STATES PATENT OFFICE

149,655

DESIGN FOR A COMBINED FLUORESCENT AND FLOODLIGHT FIXTURE

Stanley E. Lindahl, Los Angeles, Calif.

Application February 17, 1947, Serial No. 136,969

Term of patent 3½ years

(Cl. D48—23)

To all whom it may concern:

Be it known that I, Stanley E. Lindahl, a citizen of the United States and resident of Los Angeles, Los Angeles County, State of California, have invented a new, original, and ornamental Design for a Combined Fluorescent and Floodlight Fixture, of which the following is a specification, reference being had to the accompanying drawing, forming a part thereof.

In the drawing, the figure is a perspective view of a combined fluorescent and floodlight fixture, showing my new design. The panel of the end not shown is similar in appearance to the end shown.

I claim:

The ornamental design for a combined fluorescent and floodlight fixture, as shown and described.

STANLEY E. LINDAHL.
